PORATION OF MASSACHUSETTS

ATTACHMENT PLUG RECEPTACLE

Application filed July 14, 1927. Serial No. 205,708.

This invention relates to an attachment plug receptacle and more especially to a duplex receptacle of that type adapted to be mounted in the floor or wall flush with the 6 surface thereof.

The general object of the invention is to provide a receptacle of the character described which is extremely simple and compact in construction with a minimum number 10 of parts, which is efficient and durable in operation and which may be made and assembled at a very low cost of construction.

Another object of the invention is the 15 provision of a one-piece receptacle which, with the exception of the ordinary face-plate, is complete and ready for installation.

A further object is the provision of a receptacle of shallow construction to facilitate 20 mounting in thin partitions or shallow recesses.

Other objects of the invention will be more specifically set forth and described herein- 25 after.

In the drawings illustrating the preferred form of the invention, Figure 1 is a plan view 30 of a receptacle constructed in accordance with our invention; Fig. 2 is a longitudinal vertical sectional view of the same on line 2—2 in Fig. 1; Fig. 3 is a reversed plan view with certain parts broken away to show the interior construction; Fig. 4 is an end elevation of the receptacle showing the construction of the 35 means for mounting the receptacle; Fig. 5 is a similar view showing a modified form of mounting construction; Fig. 6 is a plan view of the back face of one end of the receptacle illustrating another modification of the mounting means; Fig. 7 is a detailed sec- 40 tional view of said modified form of mounting means shown in Fig. 6 and Fig. 8 is a detail sectional view of the contact plate fastening means.

Referring to the illustrated embodiment of 45 the invention, 10 designates a one-piece body or block of insulating material having on its outer face two circular bosses 12 projecting slightly from said face and fitting within circular openings in the face-plate 14 when 50 the receptacle is permanently mounted in

position. On its inner or back face the body 10 is recessed at 16 and opening into said recess from the outer face are two sets of slots or openings 18 and 19 for receiving the jack-blades of two electric plugs simultaneously. As shown each set comprises four such openings in each boss, two of said openings 18 to accommodate plugs having blades arranged in tandem and the other two 19 to take blades arranged in parallelism. 55

On the back face of the body 10 and within the recess 16 are mounted two contact-plates 20, each of which comprises a strap designated as 20 having each end provided with two bifurcations or contacts 22 turned upwardly 60 and projecting, one into a slot 18 and the other into a slot 19, each contact-plate, therefore, having four slot entering contacts. The end of each contact is bent over in reverse direction so that when it is inserted in its 65 respective slot the free end of the contact is forced inwardly so that the contact engages both sides of the slot at all times and thereby insures a good contact when the blade of the electric plug is inserted between the free end 70 of the contact and the side of the slot.

To afford sufficient room for the insertion of the contact 22 and at the same time to prevent the jack-blade entering on the wrong side of the contact, each jack-blade slot is enlarged at its recess end and a shoulder 23 is thereby formed under which the bent portion of the contact lies (Fig. 2). The free end of each contact may have the usual projecting boss 25 for engaging a corresponding depression in the jack-blade in engagement therewith so that the force required to effect a separation insures a quick withdrawal of the jack-blade and prevents arcing. 85

The two contact-plates 20 are each held in 90 fixed separated position upon the rear face of the body by a terminal screw 24 passing through the body 10 and having its shank end threaded into a terminal plate 26 mounted on a recessed shelf 28 formed in the top face 95 of the body. A binding screw 30 is carried by each of said terminal plates for connecting an electric supply conductor and each plate is provided with an upturned lug 32 for holding the end of the conductor under 100

the binding screw. The heads of the terminal screws 24 should be flush with the outer surfaces of the terminal plates and to accomplish this result, the holes in the body for receiving the terminal screws 24 are bevelled 5 on the inner face of the body to receive the countersunk material surrounding the hole in the terminal plate as shown in Figure 8 in detail.

10 For insulating the contacts, we provide a sheet or plate 34 of insulating material cut to fit the recess 16 which may be fastened within said recess by any suitable means. Preferably, however, it is held in position by screws arranged centrally and at both ends by the means used for mounting the receptacle in permanent position. Since the heads of the terminal screws 24 are countersunk in the terminal plates as shown in Figure 8 the sheet 20 or plate 34 engages the contact plates. Each end of the insulating plate 34 is held in place by an end bracket 42 mounted on one end of the body and locked against lateral or vertical movement, said bracket having its upper 25 end turned outwardly and provided with a hole 45 to permit fastening to a support and its lower end turned inwardly to secure the end of the insulating plate in position. The body portion of each bracket 42 is provided 30 with two side ears 44 and that portion of the bracket with the ears is set in a correspondingly shaped recess in the end of the body whereby, so long as the bracket is in engagement with the body 10, it is locked against vertical and lateral movement, thereon. The lower end of each bracket 42 is turned under 35 one end of the insulating plate 34 and that portion of the bracket is extended on both sides, each extension 65 being turned upwardly through an open slot in the perforating plate and bent over upon the inner face of said plate (Fig. 4). The two brackets are by this construction locked on the two ends of the body and when the receptacle is permanently 40 mounted, the brackets support the body and the two ends of the insulating plate.

In Fig. 5, a modified form of interlocking means is shown in which the body portion of the bracket 47 is provided with a vertical opening adapted to receive a projecting boss 48 formed on the end of the body 10 thereby locking the bracket against vertical and lateral movement when in final position. In Figs. 6 and 7 another modification of bracket 55 is shown in which the bottom portion thereof lies in one plane and is secured to one end of the perforating plate 34 by screws 50 or other suitable attaching means such as eyelets or rivets. In this last modification, the 60 lower portion of the bracket 46 is extended laterally the entire width of the insulating plate and thereby serves to hold it in fixed position when the receptacle is permanently mounted.

65 It will be observed that the receptacle is of

extreme simplicity of construction and that all unnecessary screws and other parts have been eliminated thereby conduced to economy of manufacture which is a consideration of great importance in devices of this character. 70

Although we have shown our invention as embodied in a receptacle having two pairs of contact slots or openings to accommodate plugs with tandem and parallel blades, it is 75 to be understood that this form of the invention is merely illustrative and that the invention may be embodied in either single receptacles with but one pair of contact slots or in duplex receptacles adapted to receive simultaneously a plurality of plugs. 80

What we claim is:

1. An attachment plug receptacle comprising a one-piece insulating body recessed in its inner face, a plurality of pairs of jack-blade 85 slots entering said recess from the outer face of said body, a pair of contact plates mounted in said recess, each contact having each of its two ends provided with a pair of contacts projecting into two of said jack-blade slots, a pair of terminal plates, a pair of screws, each of said screws connecting one of said terminal plates with one of said contacts and serving to hold said terminal plate and said contact in fastened position, a sheet of insulating material mounted within said recess and underlying said contacts, means for centrally fastening said insulating sheet to said body and means for mounting said receptacle in permanent 100 position, said mounting means being adapted to serve as means for holding the two ends of said insulating sheet in locked position within said recess. 105

2. An attachment plug receptacle comprising a one-piece insulating body recessed in its inner face, a plurality of pairs of jack-blade slots entering said recess from the outer face of said body, a pair of contact plates, each plate having a plurality of pairs of contacts projecting into said slots, a pair of terminal plates, a screw connecting each of said terminal plates with its respective contact plate, and serving to hold its connected members in place, a sheet of insulating material mounted on the inner face of said body and underlying said contact plates and a pair of brackets for mounting said receptacle in permanent position, said brackets being adapted by interlocking therewith to hold the ends of the insulating material locked on said body. 115 120

3. An attachment plug receptacle comprising a one-piece insulating body with jack-blade slots, contact plates secured to the inner face of said body and having contact portions projecting into said slots, a sheet of insulation underlying said contact plates and centrally secured to said body and two brackets for supporting said receptacle in 125 130

permanent position mounted one on each end of said receptacle; each of said brackets being interlocked to one end of said body and having a portion supporting one end of said 5 insulating plate.

4. An attachment plug receptacle comprising a one-piece insulating body recessed in its back or inner face and provided with jack-blade slots, contact plates mounted within 10 said recess and having contact portions projecting into said slots, a sheet of insulation underlying said contact plates and centrally secured to said body and two brackets for supporting said receptacle in permanent position mounted one on each end thereof; said 15 body and each of said brackets being provided with interlocking means preventing vertical and lateral movement of said bracket on said body and each of said brackets having a portion for supporting one end of said insulating plate within said recess.

5. An attachment plug receptacle comprising a one-piece insulating body with jack-blade slots, contact plates secured to the inner 20 face of said body and having contact portions projecting into said slots, a sheet of insulation underlying said contact plates and two brackets for supporting said receptacle in permanent position mounted one on each end 25 of said receptacle, each of said brackets interlocking with one end of said sheet of insulation to hold the same locked on said receptacle.

In witness whereof, we have hereunto set 30 our hands this eleventh day of July, 1927.

GUSTAF A. JOHNSON.
ARTHUR A. JOHNSON.
